(No Model.)

C. SCHLICKEYSEN.

APPARATUS FOR MIXING MORTAR, CONCRETE, &c.

No. 316,069.

Patented Apr. 21, 1885.

UNITED STATES PATENT OFFICE.

CARL SCHLICKEYSSEN, OF BERLIN, GERMANY.

APPARATUS FOR MIXING MORTAR, CONCRETE, &c.

SPECIFICATION forming part of Letters Patent No. 316,069, dated April 21, 1885.

Application filed June 28, 1884. (No model.) Patented in Belgium February 29, 1884, No. 61,327, and in England March 1, 1884, No. 4,224.

To all whom it may concern:

Be it known that I, CARL SCHLICKEYSSEN, a subject of the Emperor of Germany, residing at Berlin, Prussia, Germany, have invented 5 certain new and useful Improvements in Apparatus for Mixing Mortar, Concrete, &c., of which the following is a specification.

This apparatus is intended for mixing sand, lime, cement, or other materials in one mixing-vessel, (similar to clay-cutting machines,) then conveying the material automatically to another mixing-vessel and mixing it with other substances, especially gravel or quartz or pieces of stone, and adding water, then conveying 15 the material to one end of the vessel, where it is either allowed to drop out or is first raised to a higher level by gutter-elevator and then discharged.

The accompanying drawings form a part of 20 this specification and represent what I consider the best means of carrying out the invention.

Figure 1 is a transverse section on the line $x x$ in Fig. 2. Fig. 2 is a plan view, partly 25 in section. Fig. 3 is a transverse section on the line $y y$ in Fig. 2. Fig. 4 is an enlarged sectional detail view of one of the mixer-arms in the second trough. Fig. 5 is a vertical cross-section through the said second trough. 30 Fig. 6 is a part plan of the mixer-arms therein.

Similar letters of reference indicate corresponding parts in all the figures where they occur.

The first mixing-trough, A, is partly or wholly 35 open at the top. The materials—such as lime, sand, cement, or other materials—are thrown in at one end, A', Fig. 2, in a dry or wet state, and by means of the mixer-arms A³, Fig. 3, 40 on the revolving shaft A² well mixed, and by the skewed or screw-thread position of blades on the arms simultaneously conveyed in the well-known manner to the other end, where it is let out by a slide-valve through an 45 opening, A⁴, or by another slide-valve through another opening, A⁵, conveyed into an adjoining second mixing-trough, B, situated at a little lower level, and into which other materials—as gravel, pieces of stone, lime, and water— 50 are charged. All the materials are mixed by revolving mixer-arms, such as B⁴ B⁵, Figs. 4,

5, and 6, in this second trough and conveyed to the opposite end. This end is provided with a slide-valve and opening, B', for discharging the mixed material, and with another 55 slide-valve and opening, B², by which the material required may be admitted to a continuously-working gutter-elevator for raising the concrete or other made material to the required height and discharging it there. The gutter-elevator is somewhat wider than the opening B² in the second mixing-trough, from which it rises. There is a shield, B³, Fig. 1, below the endless gutter, and fixed to the second mixing-trough, B, for preventing the concrete from 60 falling through instead of being taken up by the cross-boards D³ in the gutter-elevator. As the aforesaid opening B² to the second mixing-trough, B, is open at the top and wider than the largest stones in the concrete, no jamming 65 of the concrete can take place, and the mixing, lifting, and discharging operations are not interrupted. An adjustable board, C⁵, near the top of the elevator is for directing the discharge 70 of the concrete.

In mixing concrete it is of importance that the smaller particles be mixed as dry as possible, then to add water so as to form an even grout, and to mix the latter with gravel, pieces of stone, lime, or the like. These requirements are fulfilled by my apparatus.

In place of the two mixing-vessels shown three or more can be arranged, of which one is always conveying the material automatically into another, and the material is being mixed 85 there with other substances. This mixed product is fed to the next succeeding trough.

It is new to use for coarse concrete a mixing-trough with knives or arms similar to those for mixing clay, and this is only possible by providing means whereby all jamming 90 of the pieces of stone between the knives and the trough-walls is prevented, as well as every other cause of clogging or stopping of the action. For this purpose I form this second 95 mixing-trough, B, almost the whole length with long narrow upper slots, and the walls of the inlet hopper part are tapering outward about radially from the trough, (and not tangential, as with the aforesaid first mixing-trough, A, 100 and as usual,) in order thus to prevent jamming between the mixer-arms and the trough-

walls. The knives or arms B⁴ are also, as shown in Figs. 4, 5, and 6, provided with steel edge-pieces B⁵, which have projecting points or wedges that come near the trough-walls.

5 When worn these pieces may be replaced by new ones, or be forced a little farther out till they almost touch the walls; also, for the same purpose at those places where the knives pass I provide the inner walls of the trough with 10 strips of sheet steel B⁶, Figs. 5 and 6, riveted on at one lower end, and reaching up to the hopper, where they are provided with hinge-pins B⁷, to which is connected a knee-lever, B⁸, and adjusting-screw B⁹, for drawing the 15 band up around the knife ends, which thus scrape against it. These steel bands are only needed on the side where the knives rise, as there is no tendency to jam on the other side, and they are cut off slanting at B⁶ in order 20 that the knives may not jam the pieces of stone here, but slide past the slanting edge.

Opposite the two outlet-openings B' B² the mixer-shaft F is provided with one or more flaps, or a double flap, G G, (see Figs. 1 and 2,) for the purpose of insuring that the mixture is led more certainly toward those openings. These flaps G are weakly secured, so that they would eventually give way and turn on the shaft in case a heavy obstruction—such 30 as stone—should be jammed between a flap and the wall of the trough. When the obstruction had been removed, it would again turn around with the shaft and fulfill its purpose.

I claim as my invention—

35 1. In a machine for mixing concrete, two or more mixing-troughs, each having revolving shafts and arms, arranged side by side, and the exit end of the primary trough connected with the entrance end of the secondary trough 40 by separate gateways controlled by adjustable gates or valves combined with a single power and connections, whereby two or more ingredients are mixed in the primary trough

and automatically carried to the next trough, mixed with other ingredients, and automatically carried in the opposite direction from the second trough, as set forth. 45

2. The construction of the mixing-troughs, and especially constructing the second trough with mixer-arms provided with spur-like projections, with upper slot-openings, with about 50 radial upper hopper-walls, and with yielding parts, for the purpose of preventing jamming, substantially as set forth.

3. In a mixing-trough, in combination with 55 a revolving shaft carrying knives, the series of correspondingly broad plates or aprons of sheet metal, each fixed at one end to the wall, and provided with means for tightening at the opposite end, arranged, as shown, so that the 60 edges of the knives touch the yielding apron, and thus prevent jamming, as herein specified.

4. In a mixing-trough, the yielding aprons B⁶, having a beveled or inclined receiving end, in combination with provisions for adjusting 65 and tightening the other end, and with a revolving shaft having blades or knives revolving in contact with or near such apron, substantially as herein specified.

5. In combination with the knife-shaft of 70 a horizontal clay-mixer, one or more ejecting-wings mounted opposite the discharge-openings in such manner that the mixed material as it arrives is discharged or pressed out, but so that they remain stationary in case of jamming of stones between the wings and wall to 75 avoid breakage while the shaft continues to turn, all substantially as herein specified.

In testimony whereof I have hereunto set my hand, at Berlin, in the presence of two sub- 80 scribing witnesses.

CARL SCHLICKEYSSEN.
